George Reynolds of East Hartford, Connecticut
Letters Patent. (Patented Feb. 7, 1834.)

The Schedule referred to in these letters Patent and making part of the same containing a description in the words of the said George Reynolds, himself of his improvement in the machine for dressing old feathers, and preparing new ones for putting into beds.

To all to whom these presents shall come, Be it known that I, George Reynolds of East Hartford in the County of Hartford and State of Connecticut, have invented a new and useful machine for dressing old feathers and preparing new ones for beds, and that the following is a full and exact description of the construction and operation of the said Machine as invented by me. The machine consists of a cylinder or barrel of sheet iron, three feet more or less in length, and 18 inches more or less in diameter. On one side of the cylinder is a body, which for convenience should be near to the whole length of the cylinder, and of a convenient width for putting in and emptying out the feathers. Through the centre of the cylinder from end to end runs a wooden shaft of a size sufficient for inserting dressing pins, which may be of large wire, or of any material which may be thought suitable. The number and length of these pins may be varied according to the size and length of the machine, and the judgment of the operator. In the centre of each end of the cylinder is a hole through which the gadzengs pass and run into the end of the shaft. The gadzeng connected with the crank has a nut on it screwed to the end of the cylinder, which is screwed up so as to pinch the sheet iron between the nut and the end of the wooden shaft, holding the cylinder and shaft firm together. These gadzengs may be screwed out and the shaft taken out at pleasure. The end of the cylinder does not the crank is not fastened to the body of the cylinder but made with a narrow rim similar to the cover of a snuff box, and lets close within the end of the cylinder and can be taken out when necessary. To use this machine if in a room where

a fire place. a sort of stove or pen suited to the size of the machine may be built up of Brick on the hearth, filling up the fire place except an opening at top for taking off the smoke.

In the front of the Brick work several small holes should be left for a draught of air to feed the fire, which is made on the bottom. over the top a cover of sheet iron or something which will be secure against fire, should be placed to procure the heat, and carry off the smoke into the chimney. This cover or lid may be hung with hinges so as to raise up or shut down at pleasure. In the ends of this Brick work should be left narrow openings, just sufficient to let down the guides, so as to bring the machine within a proper distance of the fire. At the bottom of these openings, or covers, suitable boxes are placed for the guides, to turn upon. The feathers to be dressed, are first well washed, and when about half dry are in proper order for dressing. A sufficient quantity for the machine to operate upon, are now put into it, and placed over the fire, and turned slowly, till the feathers are entirely dry, which may be known by the ceasing of steam coming from them through a small hole, or hole, made in one or both of the ends, of the cylinder for that purpose. The feathers are carried round with the cylinder till they come to the top, when they fall to the bottom, the pins at the same time separating the feathers, and working them up loose, and however dead and matted before, they come from the machine as light and lively as any new feathers. By this process every bad smell is entirely destroyed, and every insect or fly is also destroyed. When one batch or filling of the machine is done, the machine is taken out and placed upon stanchions, when by opening the door and turning it down, the feathers are emptied out, then turning the door up again to the top the machine is filled again and placed over the fire.
